(57) **CLAIM**

The ornamental design of a head shower, as shown and described.

DESCRIPTION

FIG. 1 is a perspective view of a head shower according to the present invention

FIG. 2 is a left side elevational view of the head shower of FIG. 1, the right side elevational view being identical thereto. FIG. 3 is a front elevational view of the head shower of FIG. 1, the rear elevational view being identical thereto.

FIG. 4 is a top plan view of the head shower of FIG. 1; and, FIG. 5 is a bottom plan view of the head shower of FIG. 1. The dashed lines illustrate environment that does not form a part of the present invention, and no claim is made to the material illustrated with dashed lines.

1 Claim, 4 Drawing Sheets

FIG. 1

FIG. 2

FIG. 3

FIG. 4

FIG. 5
